(30) **Foreign Application Priority Data**

The ornamental design for a taillight for a vehicle, as shown and described.

Jul. 18, 2017 (DE) 40 2017 100 835

DESCRIPTION

(51) **LOC (11) Cl.** **26-06**

This application contains subject matter related to the following co-pending U.S. design patent applications:

(52) **U.S. Cl.**

Application Ser. No. 29/624,209, filed Oct. 31, 2017 and entitled “Vehicle, Toy, and/or Replicas Thereof;”

USPC **D26/28**

Application Ser. No. 29/632,573, filed herewith and entitled “Taillight for a Vehicle”; and

(58) **Field of Classification Search**

Application Ser. No. 29/632,575, filed herewith and entitled “Taillight for a Vehicle”.

USPC D26/28-36

FIG. 1 is a front view of a taillight for a vehicle according to the design;

CPC B62J 6/001; B62J 6/02; B60Q 9/13; B60Q

FIG. 2 is a left perspective view thereof;

9/135; B60Q 9/1375; F21S 48/00; F21S

FIG. 3 is a right perspective view thereof;

48/10; F21S 48/115; F21S 48/225; F21S

FIG. 4 is a left side view thereof;

48/1233; F21S 48/1266; F21S 48/1388;

FIG. 5 is a right side view thereof;

F21S 48/2268; F21V 21/04

FIG. 6 is a top view thereof;

See application file for complete search history.

FIG. 7 is a bottom view thereof; and,

(56) **References Cited**

FIG. 8 is a rear view thereof.
